UNITED STATES PATENT OFFICE

2,129,164

TYPE CASTING MACHINE

Rutherford B. Chase, Chicago, Ill.

Application August 23, 1937, Serial No. 160,432

2 Claims. (Cl. 22—80)

The invention relates to improvements in type casting machines and primarily to crucibles therefore whereby the type metal is brought to and maintained in a molten or fluid state, the crucible providing means for feeding this metal to a reservoir from which it is fed to the type molds.

It is an object of this invention to mount the crucible in a manner relatively to the reservoir to accomplish movement of the crucible with respect to the reservoir to thereby facilitate access to certain elements of the reservoir and thus reduce the time consumed in removal and replacement of these elements for the purpose of cleansing said elements.

It is an additional object of the invention to construct the crucible so that it may readily be associated with the type casting machine and be bodily removed from the machine.

It is another object of this invention to provide a crucible having the above characteristics with means for regulating the feeding of the metal from the crucible to the reservoir in accordance with the amount of metal withdrawn from the reservoir, this means being automatically operable to prevent feeding of metal to the reservoir to thus allow movement of the crucible relatively to the reservoir and other elements of the type casting machine without fear of the discharge of molten metal and consequent injury to the workman whose duty it is to maintain the machine in proper condition.

It is an object of the invention to provide the crucible with means such as a float or other device operable by the amount of metal in the reservoir to control feeding of the molten metal from the crucible and to combine therewith means for rendering the float ineffective to operate the valve and permit the latter to automatically close and thus prevent accidental discharge of metal from the crucible when the latter is moved out of cooperation with the reservoir to expose the above mentioned elements of the type casting machine.

It is a further object of the invention to provide means whereby the float may be arranged in the manner and for the purpose just referred to, and thus allow unitary movement thereof with the crucible.

It is another object of the invention to provide a separable connection between said float and the valve for controlling flow of metal from the crucible to thus allow the crucible to be moved with respect to the float to thereby provide means which compensates for a condition preventing unitary movement of the float and crucible.

The invention has these and other objects all of

which will be explained in detail and more readily understood when read in conjunction with the accompanying drawing which illustrates one embodiment of which the invention is susceptible, it being understood that the changes and modifications may be resorted to without departing from the spirit of the appended claims forming a part hereof.

In the drawing, Fig. 1 is a side view of a portion of a type casting machine showing the device applied thereto.

Fig. 2 is a perspective view of the crucible shown in Fig. 1.

Fig. 3 is a sectional view taken on line 3—3 of Fig. 1.

The invention is designed primarily for use with a type casting machine and particularly with the reservoir which supplies metal to the molds. Machines of this character include a reservoir, having a pump for feeding molten metal to the mold, this pump requires daily attention and removal from the reservoir for cleansing purposes. The crucible which supplies molten metal to the reservoir is stationarily mounted with respect to the reservoir and other elements of the type casting machine it being bolted in place thus requiring complete separation from the type casting machine in order to accomplish access to the pump in order to cleanse the latter. This operation consumes a period of time which is materially reduced by the structure herein shown and described.

This reservoir is designated 10 and involves the use of the pump generally designated 11 having a pump shaft 12, the latter being connected with one arm such as 13, of the bell crank lever generally designated 14. This bell crank lever has an arm 15 which is provided with a roller 16 for cooperation with the cam 17, the latter causing movement of the bell crank lever and actuation of the pump 11. The cam 17 drives the bell crank lever in one direction it being actuated in the opposite direction through the agency of the coil spring 18. This bell crank lever is pivotally connected at 19 to the bracket generally designated 20, which is secured to the main frame of the type casting machine. This bracket 20 has an apertured boss 21 provided for the reception of the mold disc lever shaft of the type casting machine, this shaft is removed and the crucible hanger 22 is substituted therefor. This hanger 22 supports the crucible 23 for swinging movement. Usually those structures employed for melting the metal and bringing it to a fluid state, so that it may be fed to the reservoir or melting pot 10, are stationarily mounted with respect to the type cast-

- ing machine and thus require separation and dis-
association from the main frame of the type cast-
ing machine before access may be had to the pump
and pump shaft, thus making it difficult and more
or less laborious in order to permit of access to
the pump and pump shaft respectively designated
11 and 12 to accomplish cleansing of these ele-
ments. Since these last mentioned elements must
be cleansed at least once a day, it becomes obvious
10 that considerable time is lost in performing this
necessity and that by providing a structure which
may be readily moved with relation to the reser-
voir or melting pot 10 without removal or disas-
sociation from the type casting machine, acces-
sibility to these elements is more conveniently ef-
fected, which reduces the time period necessary in
order to remove and cleanse the elements of the
pump such as 11 and 12. The crucible generally
designated 23 is provided with means 24-24
20 which are passed over the end of the hanger 22
and thus provide means whereby the crucible is
hinged, permitting said crucible to be arranged in
a position relatively to the elements 11 and 12 in
a manner to facilitate accessibility to them to
accomplish their removal from the reservoir 10.
The crucible generally designated 23 consists
of an outer casing 25, and a melting pot 26, which
are insulated from each other through the medium
of the insulation 27. The outer casing 25 ex-
30 tends below the bottom of the pot 26 and provides
a housing for a heating element generally design-
ated 28, which in the present instance consists of
a gas burner having the regulator 29, the valve 30
and the hose connection or nipple 31.
The structure just described includes a cover
generally designated 32, consisting of two ele-
ments respectively designated 33 and 34, the lat-
ter being hinged at 35, to permit this portion 34
40 of the cover to be moved to allow metal slugs
and shavings to be introduced to the crucible. The portion 33, is provided with a vent opening
36, to allow escape of fumes from the interior
of the crucible. The bottom of the pot 26 is pro-
vided with a tubular extension 37 which provides
45 an outlet from the pot 26 of the crucible to feed
metal to the reservoir 10. This tubular extension
37, is provided with the valve seat 38, with which
the needle of the valve 39, is adapted to coop-
erate, to control the flow of metal through said
50 valve. The stem 40 of the needle valve 39, is
mounted for guidance in the member 41, and said
stem is connected with the lever arm 42 at 44,
said lever arm being pivoted at 43. The lever
arm 42 projects beyond the casing of the crucible
55 and is connected with the float rod 44', the lat-
ter being provided with a float 45 which is ar-
ranged in the melting pot or crucible 10 and is
provided to actuate the needle valve 39, in ac-
cordance with variations in depth of the molten
60 metal contained in the melting pot or reservoir
10. The float rod generally designated 44' is
comprised of two sections 46 and 47, which are
connected with each other through the agency
of the turn buckle 48, which provides means for
varying the position of the float in the reservoir.
The float rod 46 is connected with the lever arm
42 through the agency of a separable connection
49, to thus disconnect the float and lever and
allow the valve 39 to automatically close.
70 To provide the separable connection just re-
ferred to, the upper extremity of the section 46
is formed with an eyelet 50, which is passed over
the end lever arm 42, it being held in the position
thereof shown in Fig. 2 through the agency
75 of the separable pin 51. It will be noted that

one portion of the arm 42, such as that extend-
ing between the stem 40 and the pivot 43, is of a
greater length than that portion extending from
the pivot 43 to the float rod, and thus when the
connection between the lever 42 and the rod 44 5
is separated, the valve comprised of the seat 38
and needle 39 will be automatically closed and
thus prevent escape of molten metal from the
crucible when the latter is moved from the posi-
tion thereof shown in Fig. 1, to a position to ex- 10
pose the elements such as the bell crank lever 13
and the piston shaft 12.

Means is provided for locking the valve lever
arm 42 in this last mentioned position. This
means in the present instance consists of the ele- 15
ment 52 which is pivotally connected to the cover
of the crucible at 53 it being movable crosswise of
the lever arm 42, and parallel therewith to thus
lock and release the lever arm. Means is provided
to guide the lower end of the float rod generally 20
designated 44. This means is designated 54 and
is in the present instance formed of a pair of
spring fingers 55, which will allow the crucible
and other elements such as the lever 42 to be dis-
connected from said float rod and be moved in 25
unison with relation to the float rod 44, should a
condition at any time exist in which the float rod
is held in the reservoir against movement with
the crucible. Manifestly the structure just re-
ferred to will also allow the float and rod to be 30
separated from the crucible and be removed from
the reservoir should this be found desirable.

The invention also contemplates the provision
of means whereby the float rod and the float
may be removed from the melting pot or reservoir 35
10 and be held in an elevated position, to thereby
allow the float rod to be moved in unison with
the crucible, when the latter is moved upon the
pivots 24-24. To this end a forked spring brack-
et 56 is provided for the reception of the float 40
rod 44, after the connection generally designated
49 has been uncoupled, it being understood that
the float and float rod 44 are elevated and ar-
ranged with respect to the spring element 56 so
that a portion thereof such as the turn buckle is 45
arranged for cooperation with the element 56 to
thereby hold and retain the float and float rod
in an elevated position which thus allows unitary
movement of the float and float rod with the
crucible as above explained.

The heating element generally designated 28 is
provided with a tubular extension 57 which is
arranged adjacent the feed pipe 37, to thus heat
said pipe 37 and thus melt any solidified metal
left in the crucible from the previous days' oper- 55
ations.

From the foregoing explanation of the inven-
tion it is believed manifest that an arrangement
is provided whereby the crucible may be posi-
tioned to feed molten metal to the reservoir 10 60
and in addition may be moved with relation to
the reservoir and other elements of the type cast-
ing machine so as to expose the bell crank lever
13 and the pump shaft 12 resulting in greater ac-
cessibility to these last mentioned elements and
a saving in time to accomplish cleansing of the
pump 11.

It is further manifest that when movement of
the crucible 23 relatively to the reservoir 10 is
desired, and the float is lifted from the reservoir,
or the connection between the float rod and valve
mechanism is separated the valve controlling flow
of metal through the pipe 37 will automatically
close, which thus eliminates the possibility of es-
cape and burning of the person or operator whose 75

duty it is to maintain the pump 11 in an operable condition.

It is further manifest that the separable connection provided between the float rod and the valve mechanism provides means whereby the 5 crucible may be moved with respect to the reservoir 10 with the metal in the reservoir 10 in a solidified condition should the float have been inadvertently left in the reservoir 10.

10 Having thus described the invention what I claim and desire to cover by Letters Patent is:

1. In combination with a type casting machine including a reservoir arranged to deliver molten metal thereto and a crucible pivotally mounted 15 to said machine and adapted to feed molten metal by gravity to said reservoir, a float actuated valve for controlling the feeding of the metal to said reservoir, said valve and its actuating mechanism being mounted upon and carried solely by the 20 crucible to swing out of operative position when the crucible is pivoted with relation to the reservoir, safety means for positively closing said valve

before the crucible can be swung out of its operative position, and a lock for maintaining said valve in its closed position and against accidental opening while the crucible is outside of its operating position.

2. In combination with a type casting machine including a reservoir arranged to deliver molten metal thereto and a crucible pivotally mounted to said machine and adapted to feed molten metal by gravity to said reservoir, a heater arranged 10 to supply heat to said crucible, a float actuated valve operable from the reservoir for controlling the feeding of the metal from the crucible to said reservoir, said valve and its actuating mechanism being mounted upon and carried solely by the 15 crucible to swing out of operative position when the crucible is pivoted with relation to the reservoir, safety means for positively closing said valve before the crucible can be swung out of its operative position, and a lock for maintaining said 20 valve in its closed position.

RUTHERFORD B. CHASE.
